(57) **CLAIM**

The ornamental design for a drawer cabinet, as shown and described.

DESCRIPTION

FIG. 1 is a perspective view of a drawer cabinet;
FIG. 2 is a perspective view of the drawer cabinet in an open condition;
FIG. 3 is a front elevational view thereof;
FIG. 4 is a rear elevational view thereof;
FIG. 5 is a first side elevational view thereof;
FIG. 6 is a second side elevational view thereof;
FIG. 7 is a top plan view thereof; and,
FIG. 8 is a bottom plan view thereof showing the drawer cabinet in a closed position.
The broken line showing of a draw cabinet is for illustrative purposes only and forms no part of the claimed design.
